(57) **CLAIM**

The ornamental design for a tire tread of a vehicle tire, as shown and described.

DESCRIPTION

FIG. 1 is a perspective view of the tire tread of a vehicle tire, showing my new design;
FIG. 2 is a side elevational view thereof; and,
FIG. 3 is an enlarged partial front view thereof.
The tire tread of a vehicle tire pattern is repeated uniformly around the circumference of the tire structure. The dash-dot lines showing the boundaries of the claim and the broken lines depicting environmental structure (the sidewall of the tire) do not form part of the claim.
